UNITED STATES PATENT OFFICE.

WILLIAM G. ZIMMERMAN, OF EVERETT, WASHINGTON.

APPARATUS FOR THE MANUFACTURE OF WIREBOUND BOX BLANKS.

1,426,941.

Specification of Letters Patent. Patented Aug. 22, 1922.

Application filed October 2, 1918. Serial No. 256,537.

To all whom it may concern:

Be it known that I, WILLIAM G. ZIMMERMAN, a citizen of the United States, residing at Everett, in the county of Snohomish and 5 State of Washington, have invented a new and useful Improvement in Apparatus for the Manufacture of Wirebound Box Blanks, of which the following is a specification.

My invention relates to an apparatus for 10 the manufacture of wire-bound box blanks.

The object of my invention is to provide means whereby the stapling mechanism of such machines may be thrown out of operation so that no staples will be made or 15 used at predetermined points, as at the points represented by the line between the respective sides of the box and at the space which is left between successive box blanks in order to provide wire ends which may be 20 joined when the box blank is assembled in the completed box.

The purpose of my invention is to automatically cut out the stapling mechanisms at these points, and in fact at any other 25 point where it may be desired to omit the stapling action, this being done automatically, and by doing so to save the material which would otherwise be wasted in the production and driving of these staples.

30 My invention consists of a mechanism which is applied to machines of this kind for automatically securing the above results. In the accompanying drawings I have shown my invention as applied to a 35 machine of this kind, this being embodied in a type of construction which is now preferred by me.

Figure 1 is a sectional elevation taken in 40 a plane extending across the direction of movement of the conveyor, and showing one side only of the conveyor.

Figure 2 is a side elevation of that part 45 of the machine which includes a portion of the conveyor and the mechanism by which the stapling mechanism is controlled.

Figure 3 shows, in plan view, the mechanism which I have added to the machine and its relation to the staple controlling means and to the conveyor.

50 The type of machine with which my invention is designed to be used, is that in which a conveyor is employed which is provided with means for accurately placing the parts which compose the box blank, 55 namely the side boards and the cleats to which said side boards are secured. This

conveyor may be an endless chain mechanism, such for instance as is shown in U. S. patent to Craig, No. 864,955, of September 3, 1907; the two patents to Miller Nos. 60 1,142,351 of June 8, 1915 and 1,191,111, of July 11, 1916; or it may be a conveyor of the reciprocating type, such as is shown in the patents to Miller No. 815,196, of March 13, 1906, and to Inwood and Lavenberg, 65 No. 1,128,144, of February 9, 1915.

The apparatus of such machine which has been shown in connection with my invention, is based upon a machine as actually constructed which is of the endless chain 70 type of conveyor. The details of construction of the machine it is not believed necessary to show or describe in any detail.

The parts 1, 10 and 11 are parts of the endless chain mechanism which forms a 75 conveyor in this type of machine. This conveyor is provided with pockets for the reception of cleats 2 and is also provided with thin spacing ears or fingers 12, between which the side members 20 of the box are 80 placed so as to accurately position these with relation to each other.

As shown in Figure 1, the binding wire 21 is passed down over guiding wheels 23, 24, and is secured to the box parts by means of 85 staples 22. As many of these binding wires as needed are employed. One of these binding wires is placed at each end of the side boards 20 so that when stapled thereto the cleat 2 is also secured to the side board 20. 90 Additional binding wires are placed at intermediate points as required, the number of them being immaterial to my invention.

In machines of the character referred to and which are illustrated in the patents 95 named, stapling mechanisms are provided which form and drive these staples. A type of stapling mechanism which may be employed is shown in the patent of Bombardie, No. 1,203,553, of October 31, 1916. Any 100 type of stapling mechanism may however, be used which fits with the other mechanism.

The wire from which the staples are made is intermittently fed forward by means of a ratchet mechanism of which the ratchet 105 wheel is shown at 3 in Figures 2 and 3. This actuates the shaft 30 by which the wire feeding mechanism, which has been indicated at 31 in Figure 1, is caused to advance the wire a sufficient distance to form 110 the desired staple. This ratchet mechanism is actuated through an arm 32 which is

reciprocated by means of a rod 33 which is actuated from any suitable and continuously operating mechanism. The mechanism for actuating this rod is not herein shown, as this mechanism is a part of the machine as built previously to my invention.

The arm 32 carries a pawl 34. This is provided with a roller, or other laterally projecting member 35, which lies in the plane of a cam disk 36, which disk has an arm 37, by means of which it may be turned. This disk 36 has a portion 38 cut away and normally extending over the arc of movement of the roller 35. So long as the disk 36 remains in this position the pawl 34 will act at each reciprocation of the arm 32 to advance the ratchet wheel 3 one tooth. If, however, the arm 37 be thrown up so as to bring the greater peripheral surface of the disk 36 into this arc, the pawl 34 will be held away from the disk 36 and the staple feeding-mechanism will not be actuated for this stroke or the strokes occurring during the time when the disk 36 is occupying this position.

In order to install my automatic device on a machine of this sort I provide a base 4, which may be secured to any convenient part 30 of the frame, and upon this pivot a special bell crank lever 5, the pivot of this being the bolt 40. The end 50 of one arm of this lever is placed so as to be in the path of travel of the spacing ear or finger 12, which serves 35 as one of the means for positioning the side pieces of the box blanks.

The opposite arm 51 of this lever has a spring 52 secured thereto and anchored at its opposite end to a bolt or pin 55 carried 40 by the base member 4. A link 56 connects the arm 51 with a bell crank lever 6 which is pivoted at 60 to any convenient support. The other arm of this bell crank lever is pivotally connected to a link 61 which extends upwardly and is connected with the arm 37 of the disk 36 by which the operation of the pawls 34 is controlled.

It is evident that when the bell crank lever 5 is actuated by the passage of the member 12, or by any other part carried by the conveyor, so as to be thrown into the position indicated by dotted lines in Figure 3, the mechanism just described will cause the feed-controlling disk 36 to throw the pawl 55 out of action and thus prevent the feeding

action of the stapling mechanism for so long as the lever 5 is in this position.

Where it is desired to omit only one, or at the most two staples, a thin plate, such as separating plate 12, may be sufficient for this purpose. Where, however, as between the ends of adjacent box blanks, a material distance occurs during the passage of which it is desired to omit the stapling action, a member must be secured to the conveyor extending over a corresponding distance. This may be done by securing a plate 13 to the side of the conveyor, this plate being of a length corresponding to the space during the passage of which no staples are required. These plates may be made of any suitable length and are easily attached to and detached from the conveyor. In consequence of their use, the stapling mechanism may be automatically thrown out of action at any point or points desired, and the duration of these inactive positions may be varied by varying the length of the member 13 by which the same is controlled.

It is believed that the operation of my device has been clearly set forth and further description thereof is unnecessary.

What I claim as my invention is:—

1. An automatic staple - feed controlling attachment for machines of the class described, comprising tappet plates adapted to be secured to the conveyor chain, a base plate adapted to be secured to the machine frame, a lever pivoted upon said base plate and having one end positioned to be engaged by said tappet plates, a spring secured to said base plate and to said lever to swing the lever into engagement with the tappet plates, and a link secured to said lever and connecting it with the staple controlling mechanism.

2. In a device of the character described, a series of tappet plates adapted to be secured to the conveyor chain, a bell crank lever having a central cylinder forming the pivot bearing and an arm extending from each end of said cylinder, a spring acting to hold one of said arms in the path of said tappet plates, a base plate upon which said lever and spring are carried, and means connecting the other arm with the staple-feed-controlling mechanism, to throw the latter out of action when the other arm is displaced by engaging with said tappet plates.

WILLIAM G. ZIMMERMAN.
